UNITED STATES PATENT OFFICE

95,813

DESIGN FOR A LIP STICK CONTAINER

Paul H. Ganz, New York, N. Y.

Application January 16, 1935, Serial No. 54,884

Term of patent 14 years

To all whom it may concern:

Be it known that I, Paul H. Ganz, a citizen of the United States and a resident of the city, county, and State of New York, have invented a new, original, and ornamental Design for a Lipstick Container, of which the following is a specification, reference being had to the accompanying drawing, forming part thereof.

I claim:

The ornamental design for a lipstick container as shown.

PAUL H. GANZ.
